UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

SHUTTLE FEELER FOR LOOMS.

Application filed October 12, 1925. Serial No. 61,970.

To all whom it may concern:

Be it known that I, HARRY A. DAVIS, a citizen of the United States, and a resident of Hopedale, in the county of Worcester 5 and State of Massachusetts, have invented an Improvement in Shuttle Feelers for Looms, of which the following description, in connection with the accompanying drawings, is a specification, like characters on the 10 drawings representing like parts.

This invention relates to shuttle feelers for looms.

In looms of the filling replenishing type it is now the usual practice to provide a 15 shuttle feeler which, on call for replenishment of filling, is moved to a rearward shuttle-feeling position to determine whether or not the shuttle has been fully boxed, and on failure to be so fully boxed, to prevent 20 operation of the filling replenishing mechanism. Should the shuttle not have been properly boxed, the metal end of the shuttle feeler will contact with the shuttle itself, and under such conditions is liable to 25 cause injury thereto. Furthermore, should the filling be caught between the end of the shuttle feeler and the shuttle, it is liable to be broken or ruptured to such an extent as to cause filling failure on subsequent picks 30 of the shuttle. It frequently happens that a shuttle may be properly boxed; i. e., may enter the box fully and the shuttle feeler consequently move to its full rearward shuttle feeling position in front of the inner 35 end of the box, but under such conditions should the shuttle "rebound" it will engage the side of the shuttle feeler adjacent the shuttle box, and since the shuttle feeler is formed of metal, no injury is done.

One of the objects of the present invention is to provide a shuttle feeler with a shuttle engaging end formed of material which will not injure the shuttle should the shuttle feeler engage an improperly boxed 45 shuttle. Owing to the character of the material forming the shuttle engaging end of the shuttle feeler, should the filling be clamped between the body of the shuttle and the end of the shuttle feeler, it will not be broken or ruptured or crushed as heretofore, and consequently the loom may continue to run without broken filling.

As hereinbefore noted, a shuttle will sometimes rebound in the shuttle box after the 50 shuttle feeler has moved to its full rearward

position, and the present invention further provides a metal contact for impact by the end of the shuttle in case of rebound. Such metal impact member is preferably formed as a cover plate overlying the side of the 60 yielding material forming the end of the shuttle feeler, and is so related to the yielding end of the shuttle feeler as not to engage the filling should the latter be clamped between the yielding material forming the end 65 of the shuttle feeler and the shuttle body of an improperly boxed shuttle.

The invention and novel features thereof will best be made clear from the following description and the accompanying drawings 70 of one good form thereof.

In the drawings:

Fig. 1 is a perspective view of the parts at the replenishing side of the loom, showing a shuttle feeler containing the present invention and engaged with an improperly boxed shuttle; 75

Fig. 2 is an enlarged perspective detail of the shuttle engaging end of the shuttle feeler; and 80

Fig. 3 is a plan view with parts broken away, showing the rebounding shuttle engaged with the metal cover plate of the shuttle feeler.

The shuttle feeler may be of any usual 85 character and is herein shown as mounted upon a bracket 1 secured to the loom frame on which the shuttle feeler 2 is pivoted as by the bolt or stud 3. If desired the shuttle feeler 2 may be mounted for pivotal movement in the guideway formed by the guiding members 4 and 5 supported from the loom frame. 90

The lay 6 may be of usual construction and have mounted thereon the usual shuttle 95 box 7 for the reception of the shuttle 8, in which the filling carrier 9 is mounted. The parts so far described may be of usual construction and be operated in the usual manner to cause the feeler to move rearwardly 100 into shuttle feeling position to determine whether or not the shuttle has been properly boxed.

In accordance with the present invention, the shuttle engaging end of the shuttle 105 feeler is formed of material, such, for instance, as fibroid, rubber or the like, which may engage the body of the shuttle should the latter not be properly boxed, and yet not injure the shuttle. In the present instance 110

of the invention, the shuttle feeler 2 is provided with the fibroid shuttle engaging end 10 which has the upper and lower jaws 11 and 12 constituting guiding means for the 5 filling, and also impact members for engagement with the shuttle should it be not properly boxed. As shown more fully in Fig. 2, the rear end portion of the shuttle feeler is provided with an opening or cut-away portion, as at 13, forming a tongue 14 to which is fitted the non-metallic end portion 10 of the shuttle feeler. The particulars of detail in this connection, however, are not important, since such details may be varied within 10 wide limits; but the construction described provides shoulder portions 15 and 16 on the metal portion of the shuttle feeler against which the cooperating shoulders of the non-metallic end may rest.

20 Overlying the material forming the end of the shuttle feeler is a cover plate 17 which may be secured in position by any appropriate means; one form of which, as indicated in Fig. 3, consists of pins 18 which 25 may be utilized not only to secure the cover plate 17 in its overlying relation to the non-metallic material 10, but likewise also secure the yielding material 10 forming the end of the shuttle feeler in place. The pins 18 are 30 preferably formed as rivets or pins having expanded ends flush with the surface of the cover plate 17 to offer no obstruction to the proper movement of the shuttle feeler into rearward feeling position.

35 The rear edge portions of the cover plate are in general conformation with the jaw portions of the non-metallic material 10 forming the end of the shuttle feeler, but the edges of the cover plate do not extend 40 rearwardly as far as do the corresponding edges of the yielding material, with the result that not only does the cover plate not engage the shuttle should it be improperly boxed, but no injury is done the filling 45 should it be caught between the improperly boxed shuttle and the end of the shuttle feeler. As shown, the edges 19, 20, 21 and 22 of the cover plate correspond to the similar edges constituting the jaws of the non-metallic material 10, but, as will be evident 50 from Fig. 2, the edges 19, 20, 21 and 22 of the cover plate are not flush with the corresponding edges of the yielding material, and, 55 consequently, do not engage either the shuttle or filling when the shuttle feeler is moved to its rearward feeling position.

The metal cover plate 17 is primarily for the purpose of taking the impact of the end 60 of the shuttle should the latter rebound in its box, a condition indicated in Fig. 3, where it will be noted that the end of the shuttle engages the metal cover plate 17 which thereby protects the non-metallic material from injury by the end of the shuttle.

65 It is common at the present time to pro-

vide the shuttle feeler with a thread parter or a thread parter and clamp, and while such parts may or may not be employed in connection with the present invention, they are shown associated with the shuttle feeler 70 in Figs. 1 and 3. Since, however, the thread parter 23 and thread clamp 24 form no essential part of the present invention and may operate as usual, further description of these elements will be unnecessary.

75 From the construction described as a good practical form of the present invention, it will be apparent that the end of the shuttle feeler is formed of material which may engage the shuttle without injury thereto, or 80 may engage the filling between itself and the shuttle when the latter is improperly boxed without crushing or cutting the filling, since the yielding material itself presents a 85 non-cutting surface contact. The cover plate which overlies the non-metallic material 10 at the side next to the shuttle box provides a metal contact for the end of the shuttle should the latter rebound in the box, it being 90 noted that the edges of the non-metallic material 10 project rearwardly beyond the corresponding edges of the cover plate. When the shuttle feeler is in its rearward shuttle 95 feeling position and the shuttle rebounds, the end of the shuttle will engage the cover 100 plate 17 at a point opposite the backing portion 14 formed in the metal of the shuttle feeler itself and thereby further sustain the impact of the shuttle.

What is claimed is:

1. A shuttle feeler having a tip of non-metallic material formed with jaws to embrace the body portion of an improperly boxed shuttle, and a metal cover protection plate secured to the shuttle feeler and overlying the side of the non-metallic tip next to the adjacent shuttle box to be engaged by the shuttle should it rebound.

105 2. A shuttle feeler having a tip of non-metallic material secured thereto, and a metal cover plate secured to the shuttle feeler and overlying the non-metallic tip at the side next to the adjacent shuttle box to receive the impact of the shuttle should the latter rebound.

110 3. A shuttle feeler having a fibrous shuttle engaging end, and a cover plate secured to the shuttle feeler and overlying the fibrous end at the side adjacent the replenishing shuttle box, for engagement by a rebounding shuttle.

115 4. A shuttle feeler having a non-metallic shuttle engaging end, and a metal cover plate secured to the shuttle feeler and overlying the side of the non-metallic end with the rear edge of the cover plate frontward of the corresponding rear edges of the non-metallic end.

120 5. A shuttle feeler having a tip of non-metallic material for non-injurious contact

with an improperly boxed shuttle and presenting a non-cutting surface contact with the filling should it be caught between the feeler and shuttle, and a metal cover plate secured to the shuttle feeler and overlying the tip of non-metallic material at the side next to the replenishing shuttle box.

6. A shuttle feeler having a tip of fibrous material formed with shuttle engaging jaws, and a cover plate secured to the shuttle feeler and overlying the tip of fibrous material on the side thereof next to the replenishing shuttle box.

7. A shuttle feeler having a tip of non-metallic material formed with shuttle engaging jaws, and a cover plate secured to the shuttle feeler and overlying the tip of

non-metallic material on the side thereof next to the replenishing shuttle box, the rear edge of the tip of non-metallic material being extended rearwardly beyond the rear edges of the cover plate.

8. A shuttle feeler movable to its rearward shuttle feeling position on call for replenishing of filling and having a non-metallic shuttle engaging end formed with jaws, and a cover plate secured to the shuttle feeler and overlying the side of the non-metallic end next to the replenishing shuttle box to protect the non-metallic end from contact by a rebounding shuttle.

In testimony whereof, I have signed my name to this specification.

HARRY A. DAVIS.
